COMBINED FRAME AND PEDESTAL TOE
ARRANGEMENT FOR LOCOMOTIVES

Edward O. Elliott, Jenkintown, Pa.

Application June 24, 1938, Serial No. 215,609

2 Claims. (Cl. 105—172)

This invention relates generally to locomotives and more particularly to an improved combination of a frame and pedestal toe arrangement.

Ever since the adoption of the pedestal cap as the best known and acceptable method of closing the lower end of the pedestal opening in which the driving boxes and axles are disposed, the breakage of pedestal toes on locomotive frames has been a chronic condition with which the railroad industry has suffered for the lack of a more effective method and arrangement for preventing breakage of the toes or for minimizing the expense of repairs in the event of breakage. In addition to the cost of actual repairs, a very large indirect expense is often incurred by the locomotive being idle when removed from service. This can be an extremely serious matter, particularly in the event of urgent need for the locomotive on the road.

In an effort to overcome the foregoing breakage of pedestal toes, it has been attempted to make the frame sections heavier adjacent the toes, yet continued breakage of the toes has been appreciable inasmuch as an ill-fitted or loose pedestal cap or excessive stress may readily cause breakage. To repair broken pedestal toes in the past has sometimes required the removal of the frame on one side of the locomotive, thereby adding further expense caused by removal and replacement of numerous portions of the locomotive machinery, frame bracing, etc. Considerable difficulty has also been encountered in integral cast frames due to honey-combing of the metal or shifting of the mold or cores at or near the vital pedestal toe points. Such defects can readily result in rejection of the entire frame should the customer refuse to accept welding of the deficient portions.

While an integral cast steel bed has many points of superiority over the built-up or bar frame, yet the breakage of pedestal toes in the integral steel bed has been a serious problem, in fact the repair of the same is a far more serious matter than with a bar frame, since in an integral bed it is necessary to weld a very thick mass to the very light sections of the bed, whereas the bar type frame has heavier sections which permit more effective welding. Further the casting of a large integral bed structure with relatively light sections throughout, except for the large mass concentration at the pedestal toes, is a difficult problem because during cooling of the casting the shrinkage of the lighter and of the more massive sections is not the same, thus inducing shrinkage breakages at the outset of the manufacturing process, this in addition to the liability of blow

holes or honey-combing of the pedestal toes. The prior art has not provided a solution to all of the foregoing difficulties, among others.

It is an object of my invention to provide an improved pedestal toe arrangement in combination with a frame so as to overcome the many disadvantages above mentioned. A further object is to provide an improved pedestal toe and frame arrangement that is relatively simple and inexpensive in construction, operation and maintenance and yet provides ruggedness and strength against breakage under the many adverse conditions of operation.

Other objects and advantages will be more apparent to those skilled in the art from the following description of the accompanying drawing in which:

Fig. 1 is a side elevation of a portion of an integrally cast locomotive frame and bed adjacent the pedestal openings incorporated in my improved pedestal toe arrangement;

Fig. 2 is an enlarged section taken on the line 2—2 of Fig. 1;

Fig. 3 is an enlarged fragmentary longitudinal and vertical section through one pedestal toe and a portion of a pedestal cap;

Fig. 4 is a fragmentary side elevation similar to Fig. 1, but showing a modified arrangement for bolting the pedestal toe and cap to the frame.

In the particular embodiments of the invention, such as are disclosed herein merely for the purpose of illustrating certain specific forms among possible others that the invention might take in practice, I have shown a conventional type of integrally cast bed frame having usual side members 1 and 2 cross connected by suitable members 3, Fig. 2. The specific details of construction of the frame do not enter into my present invention and hence need not be further described. The side members terminate at their lower ends in flat surfaces 5, formed on what constitute rails 6 of the bed frame, while any desired number of pedestal openings 4 may be provided in the frame. The pedestal openings are formed entirely and completely by usual pedestal legs which constitute an integral part of the frame and which are separate from and independent of the pedestal toe structure.

Supported on each of the flat surfaces 5 is my improved combined supplemental bottom rail and pedestal toe member generally indicated at 7. This member extends preferably continuously from one pedestal opening to the other and has pedestal toes 8 formed integrally with the body portion of the supplemental rail 7. The main rail

6 and supplemental rail 7 are preferably held in fixed longitudinal relation to each other by transverse keys 9 and bolts 10. The supplemental rail is further secured to the frame by bolts 11 and 12 5 extending through a usual pedestal cap 13. As shown in Fig. 3 the two bolts 11 have collars 14 firmly seated in suitable recesses of rail 7 while the bolt 12 has a similar collar 15 firmly seated in the toes 8. Preferably the bolts 11 and 12 have a 10 reamed fit with the holes in the main lower rail 6 and in the supplemental rail 7 and have a loose fit in the pedestal cap 13. The specific shape of the pedestal toe 8 and mating recess in the pedestal cap may be of any conventional form usually 15 slightly tapered. Also if desired the supplemental rail may have lips 17 as shown in connection with the center supplemental rail in Fig. 1, these lips being received in suitable recesses in the side walls of the pedestal openings 4.

20 The end-most pedestal toes 18, Fig. 1, are formed on partial length supplemental rails 19, specifically half lengths. These half length supplemental rails are keyed and bolted to the main lower rail in the same manner as for the full 25 length supplemental rails.

In the modification of Fig. 4 a bar type frame is shown. The supplemental rail 20 is however shown with only a single key 21 while bolts 22 (corresponding to 11) hold the rails together 30 without any center bolts such as 10. Due to the thickness of the side walls 23 forming the pedestal openings, a bolt 24 (corresponding to 12) is threaded into the bottom rail 25. Furthermore, if desired, the simplicity of my improved arrangements 35 is conducive to extremely effective welding of the main and supplemental rails as by longitudinal welded seams 26 and 27 extending preferably for the full length of the supplemental rail. The welded seams are straight and of substantial 40 length and extend in a direct line to offer maximum resistance to spreading of the pedestal guides.

From the foregoing disclosure it is seen that I have provided a simple and yet highly effective 45 combined supplemental rail and pedestal toe which not only allows the main frame 5 to have a relatively simple flat surface 5, machined if desired, but also insures maximum strength and ruggedness for the pedestal toes. In fact this 50 supplemental rail and toe arrangement is sufficiently simple that it may be effectively and economically made of high grade fatigue resisting alloy such as nickel steel, and if desired the supplemental rail may constitute a well worked and 55 annealed forging. This improved arrangement also insures maximum possibility of a good sound casting in the simple lower rail portion if formed

as part of an integrally cast frame without any difficulties arising from imperfect pedestal toes or from failure of pedestal toes that might even have been an originally sound casting. It is furthermore seen that even though the pedestal toe 5 might break in my improved supplemental rail, yet such rail by being detachable in all forms may be readily removed with minimum time and effort merely by first removing any of the various 10 detachable holding means whether in the form of the bolts or the narrow welded seams, the removal of such holding means and the separate character of the rail eliminating the necessity of dismantling a frame side or removing other locomotive equipment attached to the frame. The fact that 15 the pedestal openings are formed entirely and completely by the pedestal legs which constitute an integral part of the frame allows the supplemental rail and pedestal toe to be removed without in any way disturbing the usual journal boxes 20 and pedestal shoes. Hence it is seen that I have provided a very effective bed frame and pedestal toe arrangement for overcoming the disadvantages that have long existed with prior arrangements and have additionally accomplished many 25 advantages not previously available in the art as hereinbefore set forth.

It will of course be understood that various changes in details of construction and arrangement of parts may be made by those skilled in the art without departing from the spirit of the invention as set forth in the appended claims.

I claim:

1. In combination, a cast frame having lower integral rails terminating at their opposite ends adjacent to and integral with pedestal structures provided with usual pedestal openings, members comprising supplemental rails supported on the under surfaces of said lower frame rails and extending continuously from one pedestal opening 35 to the next pedestal opening, pedestal toes formed on the opposite ends of and integrally with said continuous supplemental rail, detachable means for securing said supplemental and lower frame rails together, and a pedestal cap connected to the 40 pedestal toes on opposite sides of the pedestal openings whereby the tension load in one pedestal cap is transmitted through the continuously extending supplemental rail to the cap of the next 45 pedestal opening.

2. The combination set forth in claim 1, further characterized in that said under surface of the lower rail of the frame is substantially flat throughout its length and the supplemental rail has a similar flat surface to be seated against said 50 flat surface of the lower rail.

EDWARD O. ELLIOTT.
